UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

MOLDBOARD SUPPORTING AND ADJUSTING MEANS FOR ROAD GRADERS.

Application filed March 18, 1924. Serial No. 700,117.

To all whom it may concern:

Be it known that I, FRANKLIN E. ARNDT, a citizen of the United States, residing at Galion, in the county of Crawford and State 5 of Ohio, have invented certain new and useful Improvements in Moldboard Supporting and Adjusting Means for Road Graders, of which the following is a specification.

This invention relates to road graders, and 10 particularly to graders of that type wherein a mold board with its blade is mounted upon a circle, and wherein means is provided whereby the angle of the mold board to the line of draft may be adjusted.

15 One object of this invention is to provide an improved means for adjusting the inclination or angle of the mold board relative to the ground, and to provide means which will positively lock the mold board in any 20 adjusted position, which means, however, may be readily shifted into or out of its locking position.

A further object is to provide a device 25 of this character which is capable of what may be termed a coarse adjustment and a fine adjustment.

A still further object is to provide means 30 for rotating the circle in a plane parallel to the ground, and provide means for positively locking the circle at a plurality of points in any rotatively adjusted position and thus hold the circle from accidental rotation, and in this connection to provide manually operable means for readily unlocking the circle 35 and then rotating it to its adjusted position and then re-locking it.

Other objects have to do with the details 40 of construction and arrangement of parts as will appear more fully hereinafter.

45 My invention is illustrated in the accompanying drawings, wherein:—

Figure 1 is a fragmentary side elevation of a road grader constructed in accordance with my invention;

45 Figure 2 is a top plan view of the portion of the road grader illustrated in Figure 1;

Figure 3 is a top plan view of the circle and allied parts, showing the locking means for the circle, the frame structure mounted 50 above the circle being removed;

Figure 4 is a section on the line 4—4 of Figure 3;

Figure 5 is a top plan view of a portion of the circle and mold board, showing the lock-

ing means, the knees being shown in section; 55

Figure 6 is a side elevation of the construction shown in Figure 5;

Figure 7 is an enlarged section on the line 7—7 of Figure 6;

Figure 8 is an under side plan view of the 60 plate 48 and cam 52, the shaft 18 being in section;

Referring to these drawings, and particularly to Figures 1 and 2, it will be seen that I have illustrated so much of a road grader 65 as is pertinent to my present improvements, this consisting of main, longitudinally extending, somewhat divergent frame beams 10, these frame beams being connected at their forward and rear ends and being 70 arched at the middle. The forward ends of the frame beams are operatively supported upon a front axle 11, while the rear ends of the frame beams are operatively supported upon the rear axle, the wheels of which 75 are designated 12. A transverse brace 13 is mounted between the middle of the frame beams and the forward axle 11.

Swingingly mounted upon the forward axle are the rearwardly extending draw bars 80 14. These operatively support the circle 15, this circle being formed with teeth 16 defining notches between them. The circle is illustrated as operatively supported by a brace 17, through which the central vertical 85 shaft 18 passes, this central shaft carrying upon its upper end the beveled gear wheel 19. This transverse brace 17 carries at opposite points the downwardly extending angle iron ears 20. Below the brace 17 and 90 extending at right angles thereto is a transverse brace 21 which is preferably of channel iron and which is connected at its ends to the circle 15.

The circle 15, as will be seen from Figure 95 3, is approximately angular in cross section and at nearly diametrically opposite points is provided with outstanding webs 22 having vertical bracing webs 23, the under face of the outstanding web 22 being slightly 100 recessed, as at 24, (see Figure 4). Mounted upon diametrically opposite points of the circle 15 are the knees 25, the horizontal portions of which extend beneath the webs 22 and are disposed within the recessed portions 24 thereof. There are a pair of these knees on each side of the circle, as shown particularly in Figure 5, the knees extend-

ing downward and slightly forward in a curve, the knees being spaced apart. The knees are held to the webs 22 by means of bolts 26 which extend down between each 5 pair of knees, the lower ends of these bolts carrying clamps 27 and nuts 28 holding these clamps in position and holding the knees from any movement.

To the lower end of each pair of knees 10 is pivotally mounted the mold board 29, this mold board carrying a blade 30 of usual character and being connected to the knees by means of an angle iron 31 having riveted or otherwise attached thereto the upwardly 15 extending ear 32, through which the pivot bolt 33 passes. The upper portion of the mold board 29 carries upon it the ears 34, and pivoted between these ears is the locking bar 35 which, as illustrated in Figure 7, 20 is approximately T-shaped in cross section and passes between the knees 25. This locking bar is toothed upon its upper and relatively wide face, as at 36.

For the purpose of holding the mold 25 board locked in any adjusted position, I detachably and adjustably mount upon each pair of knees 25 the U-shaped yokes 37 which carries at its lower end the transversely extending shaft 38 having mounted thereon 30 the cam 39 having a transverse bar 40 at one end which constitutes a stop and handle. The cross bar of the U-shaped yoke member is provided at its ends with apertures 41 for the passage of the arms of a U-shaped 35 clamping bolt 42 carrying nuts 43. This clamping bolt embraces both of the knees 25. The cross bar of the U-shaped yoke 37 is provided with a downwardly extending lug in the form of a tooth and designated 44 40 which is adapted to engage in any one of the teeth 36.

It will be obvious now, particularly from Figures 6 and 7, that when the cam 39 is turned to the position shown in Figure 6, 45 the locking bar 35 will be forced upward and the tooth 44 will be engaged between two of the teeth on the locking bar and thus the bar 35 will be held from any longitudinal movement and the mold board will be 50 held in adjusted position. When it is desired to adjust the locking bar, however, the cam is forced in the direction of the arrow in Figure 6 to the dotted line position in this figure, which depresses the highest portion of the cam, and this permits the locking bar 35 to descend an amount sufficient 55 to detach it from its engagement with the tooth 44 and thus permit the mold board to be adjusted. When the mold board is adjusted 60 the cam is turned in the reverse direction to the arrow shown in Figure 6 until the handle 40 which constitutes a stop bears against the two legs of the U-shaped lug 37 and the cam is then in position to hold 65 and lock the bar 35 in engagement with the

tooth 44. It will be seen that the bar 35 is disposed between the two knees. Therefore, it is amply supported against lateral thrust. Inasmuch as the cam is mounted upon the yoke 37, which in turn is held to the knees by means of the U-shaped bolt 42, it follows that this yoke 37 may be adjusted along the knees to any desired point and then the mold board be shifted inward or outward by hand to change its angle 70 with relation to the ground and then the cam 39 turned so as to carry the bar 35 up into its engagement with the locking tooth 44 and lock the mold board in adjusted position. Inasmuch as the locking devices are 75 independent of each other, it follows that one may be slightly differently adjusted than the other. It will be seen from Figure 2 that the knees are curved at their forward ends concentrically to the curvature of the circle 15 and this curvature, of course, materially assists in aiding the bolts 26 to hold the knees against longitudinal movement under the strain to which the mold board is subjected.

For the purpose of holding the circle 15 in any of its rotated positions, I provide, as illustrated best in Figures 3 and 4, the locking bolts 45 which are mounted immediately beneath the annular portion 46 of the frame, these locking bolts having shanks 47 which extend inward and pass through the lugs 20, each shank 47 having at its end the yoke 48, this yoke being longitudinally slotted, as at 49. Each yoke at its point 90 of connection to the shank is formed with an angularly bent shoulder or flange 50, and disposed between the bolt 45 and the corresponding guide lug 20 are the coiled compression springs 51. Each yoke 48 at 95 its end opposite its point of connection to the shank 47 is angularly bent so as to form a flange 52 extending transversely of the length of the yoke. The shaft 18 passes through the aligned slots 49 of the yoke and 100 through the cross piece 21, as previously described.

Mounted upon the shaft 18 is the elliptical cam 53 which operates against the transverse shoulders or flanges 52. Thus when the cam is in the position shown in Figure 3, the springs 51 act to pull the shanks 47 outward so as to thrust the bolts 45 into the notches between the teeth of the circle and thus lock the circle from any rotation. 115 When, however, the cam 53 is turned to the dotted line position in Figure 3, the cam will act to draw the yokes toward each other and thus draw the bolts out of the notches between the teeth and the circle may then be 120 adjusted. It is to be noted from Figure 8 that each flange 52 is formed at its middle with a slight depression 54 within which the nose of the cam 53 engages when the cam 125 is in the position shown in dotted lines in 130

Figure 3, so that thus the cam is locked against accidental rotation without force being applied to the cam to rotate it.

For the purpose of rotating the circle and thus rotating the mold board to any desired angular position relative to the line of draft, I provide the circle with the beveled gear wheel or toothed annulus 55. Coacting with this toothed annulus 55 is a beveled gear wheel 56, which is an idle gear wheel, and is mounted in a bracket 57 carried upon the transverse brace 21. Coacting with this idle beveled gear wheel 56 is a beveled gear wheel 59 mounted in a brace 58, T-shaped in cross section, which extends between the draw bars 14. This beveled gear wheel 59 is mounted on a shaft 60. Coacting with the shaft 60 is a tubular shaft section 61 which has a universal joint connection with the shaft section 60, as at 62.

Coacting with this tubular shaft section 61 is a shaft section 63 which has splined engagement with the shaft section 61 and extends upward and forward and has a universal joint connection at 64 with a shaft 65 mounted in bearings 66 and carrying upon it the pinion or gear wheel 67. These bearings 66 are mounted upon a plate 68 carried by the forward end of the supporting frame. Likewise mounted in bearings 69 upon this plate is a longitudinally shiftable shaft 70 carrying upon it a gear wheel 71. This shaft 70 is shiftable longitudinally within its bearings and at its rear end has a universal joint connection 72 to a slidable shaft section 73, in turn having a universal joint connection 74 to a relatively long shaft section 75 extending rearward and operatively mounted, as shown in Figure 1, upon one of the frame beams 10 and provided with a handle 76 whereby the shaft may be longitudinally shifted or rotated.

Rotatably mounted in bearings 77 on the plate 68 is a shaft section 78 carrying a gear wheel 79, this shaft section 78 being connected by a universal joint connection to a shaft section 80 which extends rearward and has splined sliding engagement with a telescopic shaft section 81, the rear end of which has a universal joint connection at 82 to a shaft section 83 mounted in suitable bearings and carrying at its rear end a beveled gear wheel 84 which engages with the beveled gear wheel 19 carried on the shaft 18, this shaft 18 being the shaft which carries the cam 53 whereby the yokes 48 and the locking bolts 45 are shifted.

The shaft 75 constitutes a manually operable shaft, as will be noted, and may be longitudinally shifted or rotated. Normally the gear wheel 71 is disposed between and out of mesh with either the gear wheel 67 or the gear wheel 79. When, however, the shaft 75 is drawn rearward, it shifts the pinion 71 into engagement with the gear

wheel 79. Then by a rotation of the shaft 75, the elliptical cam 53 will be rotated to the dotted line position in Figure 3, which will retract the locking bolts 45 and hold them retracted by reason of the extremities of the cam 53 engaging in the depressions in the flanges 52. If now the shaft 75 be shifted forward so as to carry its gear wheel 71 into engagement with the gear wheel 67, it is obvious that a rotation of the shaft 75 will cause the rotation of the pinions 59 and 56, thus through the gear wheel 55 rotating the circle and carrying the mold board to any desired adjusted position. After the mold board has been shifted to this position, the shaft 75 is again retracted and engaged with the gear wheel 71 and rotated so as to carry the cam 53 from its dotted line position to its full line position in Figure 3, which permits the springs 51 to then project the bolts 45 into engagement with the teeth 16 on the circle 15. It will thus be seen that the mold board may be adjusted to any desired position and locked in this adjusted position. It will also be noted that when the locking bolts are withdrawn from engagement with the circle that they are held withdrawn by reason of the extremities of the cam resting in the notches or depressions in the transverse flanges 51.

I do not wish to be limited to any particular means for supporting the circle, as various means such as commonly employed for this purpose may be used, but I have illustrated the circle as supported at three points, the channel iron brace 17 at its forward end carrying a casting 85 acting as a guide for the bolt and being recessed at its outer end to receive the teeth 16, the brace 58 being formed with a downwardly extending lug 86, this lug being recessed, as shown at 87, so as to receive the teeth 16 between them. Thus it will be seen that the circle is supported at a plurality of points for rotary movement around the axis of the shaft 18. This circle is riveted, bolted or otherwise attached to the transverse brace 21 and to this brace the gear wheel 55 is also riveted, as shown best in Figure 2.

The mechanism which I have described gives complete command over the position of the mold board to the operator of the scraper who stands on a platform at the rear end thereof and permits the unlocking of the circle carrying the mold board and its adjustment in either direction and to any extent required while the machine is operating and then permits the relocking of the mold board in the desired position. The construction illustrated in detail in Figure 6 permits the ready adjustment of the mold board into any desired angular relation to the ground and permits the firm locking of the mold board in this adjusted position, this locking strain being resisted by the

knees themselves by reason of the fact that the locking device is bolted by the U-bolts 42 to the knees.

While I have illustrated certain details 5 of construction and arrangement of parts, I do not wish to be limited to this, as it is obvious that many changes might be made in these details without departing from the spirit of the invention as defined in the appended claims.

I claim:—

1. A road grader including a supporting frame, a circle operatively mounted thereon for rotation around a central axis, a mold 15 board carried upon the circle and oscillating therewith, a locking device mounted upon the supporting frame and held from rotation and normally engaging the circle and holding it from rotation, and a single means 20 mounted on the supporting frame whereby the locking device may be unlocked and the circle rotated in either direction.

2. In a road grader, a supporting frame, a circle operatively mounted thereon for rotation around a central axis, the circle having 25 locking notches facing toward the center of the circle, a radially disposed bolt held from oscillation with the circle and spring projected toward the notches of the circle, 30 and manually operable means for retracting the bolt and oscillating the circle.

3. In a road grader, a supporting frame, a circle operatively mounted thereon for rotation around a central axis, the circle having 35 locking notches, diametrically disposed bolts carried by the frame and held from rotation with the circle and spring projected into notches in said circle, manually operable means for simultaneously 40 retracting said bolts including a shaft coincident with the axis of said circle and mounted upon said supporting frame, a double cam mounted upon the shaft and operatively engaging with the bolts to retract 45 them when the cam is turned in one direction, and manually operable means mounted upon the supporting frame for rotating said cam.

4. In a road grader, a supporting frame, a circle operatively mounted thereon for rotation around a central axis, the circle having 50 locking notches, diametrically disposed bolts mounted on the supporting frame and spring-projected into notches in said circle, 55 slotted yokes on the inner ends of said bolts, the yokes overlapping and the slots coinciding, a shaft supported by the frame and passing downward through said slots and constituting an axial center around which 60 the circle turns, a cam mounted on the shaft and adapted to engage said yokes to retract the bolts when the cam is turned in one direction and permit the projection of the bolts when the cam is turned in the other direction, and manually operable means for 65

operating said cam mounted upon the rear end of the supporting frame.

5. In a road grader, a supporting frame, a circle operatively mounted thereon for rotation around a central axis, the circle having 70 locking notches, diametrically disposed bolts carried by the supporting frame and spring-projected into notches in said circle, slotted yokes on the inner ends of said bolts, the yokes overlapping and the slots coinciding, 75 a shaft carried by the supporting frame and passing downward through said slots and constituting an axial center around which the circle turns, a cam mounted on the shaft and adapted to engage said yokes to retract the bolts when the cam is turned in one direction and permit the projection of the bolts when the cam is turned in the other direction, and means for rotating said circle comprising a gear wheel operatively engaging 80 the circle to rotate it, and a single manually operable means for operating said cam and said gear wheel and shiftable into operative engagement with either said gear wheel or said cam and including a manually operable member mounted at the rear end of the supporting frame.

6. A road grader including a supporting frame, a circle operatively mounted thereon for rotation around a central axis, means 90 for locking the circle in any rotated position, a gear wheel carried by the circle, means for releasing said locking means including a central shaft having a beveled gear wheel, a shaft having a beveled wheel 95 engaging the last named beveled gear wheel and carrying upon it a pinion, a beveled gear wheel engaging the beveled gear wheel on the circle, a shaft carrying the last named beveled gear wheel and having on it a pinion, a longitudinally shiftable shaft carrying 100 on it a pinion adapted to be shifted into engagement with one or the other of said pinions, and manually operable means at the rear end of the frame whereby said last 105 named pinion may be shifted longitudinally or rotated.

7. A road grader including a supporting frame, draft bars pivotally mounted thereon and extending rearward from the forward end of the frame, a circle operatively mounted upon the draft bars for rotation around a central point, a vertical shaft disposed at the axis of said circle and carrying a beveled gear wheel, said circle having beveled gear teeth and having interiorly projecting locking teeth, a pair of slotted yokes through which the shaft passes, said yokes overlapping each other and having flanges at their inner ends, a cam mounted upon said shaft and coacting with said flanges whereby, when the cam is rotated in one direction, the yokes will be drawn toward each other and when rotated in the other direction the yokes will be permitted to move outward, 110 115 120 125 130

springs urging the outward movement of the yokes, locking bolts operatively carried by said yokes and engaging between the teeth of the circle, beveled gear wheels operatively 5 engaging the gear wheel on the shaft and the beveled gear teeth on the circle, and manually operable means mounted upon the supporting frame whereby the gear wheel may be rotated to thereby rotate the shaft 10 and cam or whereby the gear wheel engaged with the circle may be rotated to thereby adjust the circle.

8. A road grader including a wheeled supporting frame, draft bars pivotally connected to the forward end of the frame and extending rearward and downward therefrom, a transverse member mounted upon the draft bars, a central shaft carried by the transverse member and extending 20 below it, a circle operatively supported upon the draft bars for rotation around said shaft, said circle having a series of inwardly projecting locking teeth and having means for supporting a mold board, a beveled gear 25 wheel loosely mounted upon the shaft and operatively connected to the circle, locking means normally engaged with the teeth on the circle but retractible from engagement therewith, means actuated by said central 30 shaft for retracting said locking means, a beveled gear wheel operatively engaging the beveled gear wheel carried by the circle, means for operating the first named shaft to cause the unlocking or locking of the circle 35 and for operating said last named gear wheel to rotate the circle comprising a shaft section having a pinion thereon, a series of shaft sections flexibly connected to each other and transmitting motion from said last 40 named shaft section to the beveled gear wheel operating the circle, a shaft section having a pinion thereon, a series of flexibly connected shaft sections connecting said last named shaft section with the central lock 45 operating shaft, means for driving said pinions comprising a longitudinally movable shaft having a pinion thereon, the shaft being shiftable to engage its pinion with either of the first named pinions, a series of flexibly 50 connected shaft sections connected to said longitudinally shiftable shaft and extending rearward therefrom, and a manually operable means mounted upon the rear end of the rearmost shaft section.

55 9. In a road grader, a circle, knees connected thereto and extending downward and rearward therefrom and adapted to support a mold board, the circle being provided with outwardly projecting webs formed with recesses on their under faces within which the knees are received, and bolts passing through said webs and having clamping members engaging said knees and clamping the knees between the webs and said clamping members.

10. In a road grader, a circle, a pair of knees adapted to support a mold board, the knees each being composed of a pair of members, the circle being provided with outwardly projecting webs recessed upon their under 70 faces to receive each a pair of said members, bolts passing through the webs and between said members, and clamps carried by the lower ends of the bolts and engaging against the under faces of said members. 75

11. In a road grader, a circle, a pair of knees adapted to support a mold board, the knees each being composed of a pair of members, the circle being provided with outwardly projecting webs recessed upon their 80 under faces to receive each a pair of said members, bolts passing through the webs and between said members, and clamps carried by the lower ends of the bolts and engaging against the under faces of said members, the forward ends of said knees being curved to conform to the curvature of the circle. 85

12. In a road grader, a pair of knees, a mold board hingedly connected to the lower 90 ends of the knees, means for holding the mold board in angularly adjusted positions relative to the surface of the ground including locking bars pivoted to the mold board and extending rearward therefrom and past 95 said knees, a locking member mounted upon each knee and coacting with the first named locking member, each of said members being toothed, and means for shifting the locking bar into engagement with the first locking member and holding it in its engaged position. 100

13. In a road grader, a pair of knees, a mold board hingedly connected to the lower 105 ends of the knees, means for holding the mold board in angularly adjusted positions relative to the surface of the ground including locking bars pivoted to the mold board and extending rearward therefrom and past said knees, a locking member mounted upon 110 each knee and coacting with the first named locking member, each of said members being toothed, and means for shifting the locking bar into engagement with the first locking member and holding it in this engaged position, comprising a cam operatively supported upon the knee and in another position permitting the locking bar to shift away from the locking member and in the other position holding the locking bar in engagement with the locking member. 115

14. In a road grader of the character described, a knee, a mold board pivotally connected adjacent its lower edge to the knee, and means for operatively engaging 125 said knee and adjustable to hold the mold board in any one of a plurality of positions angular to the face of the road.

15. In a road grader, a knee comprising two parallel members, a mold board pivot- 130

ally connected adjacent its lower edge to the lower end of the knee, a locking bar pivoted to the mold board and extending between said members and having teeth on its upper face, a locking member mounted upon the knee and having a tooth with which the teeth on the locking bar are adapted to engage, a cam operatively supported upon the knee and having its peripheral face engageable with the locking bar, said cam being rotatable to a position to release the locking bar from engagement with the locking member or into position to engage the locking bar with the locking member.

16. In a road grader, a knee comprising two parallel members, a mold board pivotally connected adjacent its lower edge to the lower end of the knee, a locking bar pivoted to the mold board and extending between said members and having teeth on its upper face, a yoke mounted upon the knee and formed to provide a locking member confronting the teeth on said bar; a cam rotatably mounted in this yoke and having a peripheral bearing against the lower edge of the locking bar, the cam being rotatable to thereby cause the locking bar to move into locking engagement with the tooth on the yoke or out of locking engagement therewith.

17. In a road grader, a curved knee, a mold board pivotally connected to the lower end of the knee, a locking bar pivotally connected to the lower portion of the mold board and extending rearward therefrom and past said knee, a U-shaped yoke disposed against the rear edge face of the knee, means for adjustably clamping said yoke upon the knee, the locking bar passing between the legs of the yoke and the yoke being formed with a tooth confronting the teeth on the locking bar, and a cam mounted upon the lower end of the locking bar and having an edge bearing against the under face of the locking bar, said cam when rotated in one direction shifting the locking bar into engagement with the tooth on the yoke and when shifted in the other

direction permitting the locking bar to lower away from said tooth.

18. In a road grader, a curved knee, a mold board pivotally connected to the lower end of the knee, a locking bar pivotally connected to the lower portion of the mold board and extending rearward therefrom and past said knee, a U-shaped yoke disposed against the rear edge face of the knee, means for adjustably clamping said yoke upon the knee, the locking bar passing between the legs of the yoke and the yoke being formed with a tooth confronting the teeth on the locking bar, and a cam mounted upon the lower end of the locking bar and having an edge bearing against the under face of the locking bar, said cam when rotated in one direction shifting the locking bar into engagement with the tooth on the yoke and when shifted in the other direction permitting the locking bar to lower away from said tooth, the cam having a stop adapted to bear against the legs of the yoke and limiting the movement of the cam in opposite directions.

19. In a road grader, a knee composed of two spaced parallel members, a mold board pivotally connected to the lower end of the knee, a locking bar pivotally connected to the upper portion of said mold board and extending between said members and the knee having its upper face toothed, a U-shaped yoke disposed against the rear edge of the knee and having a locking tooth, a U-shaped clamping bolt passing around both the members and through the upper end of said yoke, the locking bar passing between the legs of the yoke, and a cam rotatably mounted between the lower ends of the legs of the yoke and having an edge bearing against the lower edge of said locking bar, said cam when rotated in one direction shifting the locking bar into engagement with said locking member on the yoke and in the other direction releasing said locking bar.

In testimony whereof I affix my signature.

FRANKLIN E. ARNDT.
